ATTORNEY

UNITED STATES PATENT OFFICE.

CHARLES A. WHITING, OF FRANKLIN, MASSACHUSETTS, ASSIGNOR TO WHITING & DAVIS COMPANY, OF PLAINVILLE, MASSACHUSETTS, A CORPORATION OF NEW YORK.

DESIGN FOR A HAND-BAG.

47,636.

Specification for Design.

Patented July 20, 1915.

Application filed April 1, 1915. Serial No. 18,618. Term of patent 7 years.

To all whom it may concern:

Be it known that I, CHARLES A. WHITING, a citizen of the United States, residing at Franklin, in the county of Norfolk and State of Massachusetts, have invented a new, original, and ornamental Design for Hand-Bags, of which the following is a specification, reference being made to the accompanying drawing, forming part thereof.

The figure is a perspective view of a hand-bag showing my new design.

I claim:

The ornamental design for a hand-bag as shown.

CHARLES A. WHITING.
